Primary Examiner—A. Hugo Word*Assistant Examiner*—Doris Clark*Attorney, Agent, or Firm*—Terry M. Gernstein[57] **CLAIM**

The ornamental design for a fence post anchor, as shown and described.

DESCRIPTION

FIG. 1 is a front, top and side perspective view of the fence post anchor showing my new design;
FIG. 2 is a front elevational view thereof, the rear being a mirror image of the front shown in FIG. 2;
FIG. 3 is a side elevational view thereof, the side opposite being a mirror image of the side shown in FIG. 3;
FIG. 4 is a top plan view thereof; and,
FIG. 5 is a bottom plan view thereof.

FIG. 1

FIG. 2

FIG. 3

FIG. 4

FIG. 5
